His Attorney

UNITED STATES PATENT OFFICE.

JOHN M. SHIMER, OF WILKINSBURG, PENNSYLVANIA, ASSIGNOR TO WILSON-SNYDER
MANUFACTURING COMPANY, A CORPORATION OF PENNSYLVANIA.

PUMP.

Application filed April 13, 1927. Serial No. 183,357.

This invention relates to pumps and more particularly to liquid pumps of the displacement type.

An object of this invention is to provide a pump of the type set forth of such construction and arrangement as to reduce the number of joints subject to high pressure.

A further object is to provide a pump of the type set forth having an improved construction and arrangement of discharge outlet.

A still further object is to provide an improved strainer assembly for pumps of this type.

15 A still further object is to provide a device of the type set forth which will be simple and rugged in construction and easy to manufacture and assemble.

These and other objects which will be apparent to those skilled in this particular art are accomplished by means of the invention illustrated in the accompanying drawing which shows a pump provided with a combined air chamber and discharge outlet constructed in accordance with one embodiment of this invention.

The illustrated embodiment of this invention is shown applied to any standard form of displacement pump 5 having an air chamber 6 associated with the pump discharge in the usual way. A discharge port 7 is formed in the lateral wall of the air chamber and preferably below the main body portion thereof. A strainer bore 8 communicates with the outlet port and a discharge passage 9 is formed in the air chamber casting and leads laterally away from one side of the strainer bore 8.

40 A cylindrical strainer 10 is frictionally mounted at one end on an annular rib or shoulder 11 formed on the inner face of a flange or closure 12 bolted to the casting so as to close the outer end of the strainer bore 8. It will be apparent that when the flange 45 12 is secured in place the cylindrical strainer will be positioned in the strainer bore and the inner end thereof will be received within the discharge port 7 formed in the wall of the air chamber.

It will also be apparent that the material being pumped will flow from the pump discharge into the lower portion of the air chamber casting, through the discharge port 7 to the interior of the cylindrical strainer 11 through which it passes into the laterally extending discharge passage 9. All solids are thus deposited on the interior of the strainer so that they can be easily and quickly removed from the casting by unfastening the flange 12 and withdrawing the strainer. The latter can then be easily and quickly cleaned and replaced.

The present invention obviously provides a pump discharge and strainer assembly which is combined with the air chamber in such a way as to materially reduce the amount of space required for the separate parts and which at the same time reduces the number of joints subjected to high pressure in comparison to the ordinary arrangement wherein the parts are placed in separate castings.

Although I have described what I now consider to be the preferred embodiment of this invention it will be apparent that various changes, substitutions, additions and omissions can be made therein without departing from the spirit of this invention or the scope of the appended claims.

What I claim as new and desire to secure by Letters Patent is:

1. In a device of the class described, an air-chamber having a strainer bore associated therewith, a flange closing one end of said bore, a strainer mounted on said flange and positioned in said bore, and a discharge passage leading laterally away from said bore.

2. In a device of the class described, an air-chamber having a horizontal strainer bore associated therewith, a flange closing one end of said bore, an open-ended cylindrical strainer supported on said flange and positioned in said bore, and a discharge passage leading laterally away from said bore.

In testimony whereof, I have hereunto subscribed my name this 11th day of April, 1927.

JOHN M. SHIMER.
